TO WILLIAM R. HEATH, OF BUFFALO, NEW YORK.

MULTIPLYING MECHANISM.

1,174,831.

Specification of Letters Patent.

Patented Mar. 7, 1916.

Application filed April 14, 1910, Serial No. 555,347. Renewed July 23, 1915. Serial No. 41,580.

To all whom it may concern:

Be it known that I, WILLIAM J. CRUMPTON, a citizen of the United States, residing at Evanston, in the county of Cook and State of Illinois, have invented a certain new and useful Improvement in Multiplying Mechanism, of which the following is a full, clear, concise, and exact description, reference being had to the accompanying drawing, forming a part of this specification.

My invention relates to multiplying mechanism which is of particular utility in the time-keeping system disclosed in my co-pending application Serial No. 446,895, filed August 4, 1908. In this system, the workingman's wages are automatically calculated and indicated. A rate keyboard and a time keyboard are provided, the time keyboard being automatically operated by time mechanism to set up a time element in the master machine provided in the system, and the rate keyboard being automatically operated upon actuation of the workingman's number keyboard to set up the rate element in the multiplying mechanism, and this multiplying mechanism combines the elements into the wage element and transfers the wage element to the transposing mechanism, which in turn sets up the wage element on the wage keyboard, which wage keyboard in turn controls the indication of the wage element. In the multiplying mechanism in the main system of said co-pending application, however, rate elements of only a few fixed amounts could be set up, thus limiting the range of the system. A modified arrangement is shown in said application, in which several multiplying mechanisms are connected in tandem, each receiving a factor of the rate element, the several multiplying mechanisms serially multiplying together the factors to produce the complete rate element. This modification, however, involves complicated mechanism, and besides, involves considerable time in its operation.

One of the main features of my invention in the present application is to provide multiplying mechanism by means of which rate elements made up of several digits can be handled.

Another feature is the association with this improved multiplying mechanism of improved transposing mechanism in the

form of improved register mechanism, which I have disclosed in my co-pending application, Serial No. 443,802, filed July 16, 1908. The feature of this register mechanism is that the positive operation of the order members and their operation through the carry-over mechanism can be simultaneous and concurrent. By associating a register of this kind with the improved multiplying mechanism which will accommodate numbers of more than one order digit, greater speed of operation can be accomplished. The time element is set up either automatically or manually on the master machine, and the rate element is set up on the multiplying mechanism either automatically or manually. The multiplying mechanism comprises a plurality of multiplying sets corresponding to a number of decimal orders. This itself will save much time, and the order digits of the rate element instead of being set up in a certain necessary order, can be set up either separately or simultaneously, or in any order or combination. Connected with each multiplying set is a transmission gear, each gear being connected in driving relation with an order driving pinion, which pinions are adapted for connection with the driving gears of the receiving register mechanism. These pinions are also controlled by the master machine and are moved together step by step to be carried into successive engagement with the register driving gears in a manner which can be more fully explained later. The driving gears for the multiplying mechanism are also driven by the master machine. The operation of the master machine is clearly illustrated in co-pending application Serial No. 333,660, filed September 7, 1906, there being two driving shafts operating alternately, the one shaft for controlling the selection of the orders and the other shaft for controlling the insertion of entry in the selected order. The function of the master machine in my present invention is the same, the machine being connected with shafts mounting the pinions to cause longitudinal movement of said shafts to carry the pinions successively from one set of order drive wheels to the next set of order drive wheels of the register, the machine being connected with the drive gears of the mul-

tipling mechanisms to simultaneously rotate said gears after each longitudinal advance of the pinion shafts.

My invention will be more clearly understood in the following description with reference to the accompanying drawing, in which—

Figure 1 is a more or less diagrammatic outline of the various mechanisms involved in my invention, and Fig. 2 is a sectional view taken on plane 2—2 of Fig. 1.

Referring first to the register mechanism, which is substantially like that described in my copending application Serial No. 443,802 referred to, A1 and A2 represent side walls of suitable supporting framework, each side wall terminating at the front end in a bearing hub A3 and at the rear end in a bearing hub A4. Pinned in the front hubs A3 is a shaft A5, and supported in the rear hubs A4 is a shaft A6. On the shaft A5 the order indicating sets A7¹, A7¹⁰, A7¹⁰⁰, and so on, are mounted. Each set has a spur gear A8, a carrying gear A9 and a numeral wheel A10, each numeral wheel having ten digits. The members of each order set are secured together and rotatably mounted on shaft A5. On the shaft A6 sets of driving and carry-over mechanism are mounted, each comprising differential gears A25 and A26, a drive gear A27, a differential pinion A28 carried by the drive gear, a transmission gear A29, a carry-over gear A30 and a bevel gear A31, the sets following the units order set also having a bevel gear A32. Suitably mounted in bearings A33 extending from the framework are the transmission pinions A34, each connecting the bevel gear A31 of one carry-over-driving set to the bevel gear A32 of the adjacent set. There can, of course, be any number of order sets and driving and carry-over sets. The bevel gear A25 of the units carry-over driving set is rigidly secured to the shaft A6, all the other members of the sets being rotatable thereon. With the register mechanism thus far described, positive actuation of the order sets upon turning of the driving gears A27 and actuation of the order sets through the operation of the carry-over mechanism, can take place concurrently and simultaneously, as has been shown in the copending application Serial No. 443,802 referred to.

A38^a, A38^b and A38^c represent shafts, the shaft A38^b telescoping over the shaft A38^c, the shaft A38^a telescoping in turn over the shaft A38^b. Three bearings, A39^a, A39^b and A39^c, support these shafts, the bearing A39^a directly receiving the shaft A38^a, the bearing A39^b directly receiving the shaft A38^b, and the bearing A39^c directly receiving the shaft A38^c. The shaft A38^a has the keyway A40^a, the shaft A38^b has the keyway A40^b, and the shaft A38^c has the keyway

A40^c. Secured to the left end of the shaft A38^c is the transmission pinion A41^c; at the left end of shaft A38^b is secured the transmission pinion A41^b; and at the left end of shaft A38^a is secured the transmission pinion A41^a, the spacing between these pinions corresponding to the spacing between the register driving gears A27. The shafts are not longitudinally movable with respect to each other. The shaft A38^b is confined on shaft A38^c between the collars A42 and A43, and the shaft A38^a is confined on shaft A38^b between the collars A44 and A45 on said shaft. Ordinarily, the collars A43 and A45 rest against the left faces of the bearings A39^c and A39^b, respectively, and the transmission pinions A41^b and A41^c are in mesh with the units and tens gears A27 of the register mechanism, the pinion A41^a being disconnected from the register and at the right thereof. Longitudinal movement of the shaft A40^c to the left will be transmitted to collar A43 of shaft A40^b and from the collar A45 at the left end of said shaft A40^b to the shaft A40^a, and return longitudinal movement of the shaft A40^c to the right is transmitted through collar A42 to the shaft A38^b and through the collar A44 to the shaft A38^a. The shafts must thus move longitudinally together, but may rotate relatively. The means for longitudinally moving the shafts is shown at the right of Fig. 1. The head A46 at the right end of the inner shaft A40^c is held in a bearing sleeve A47, which is secured to the left end of the screw shaft A48, which screw shaft passes through the bearing A49, the screw shaft having a keyway A50 for receiving a key extending from said bearing, so that rotation of the screw shaft in said bearing is prevented. A gear A51 has screw-threaded engagement with the screw shaft A48 and extends into slot A53 cut in the bearing A49. Rotation of said gear will result in longitudinal movement of the screw shaft and of the shaft A40^c connected therewith. The gear A51 meshes with gear A54, which connects with the shaft M66 of the master machine M_m, said machine being here represented only diagrammatically, but described in full detail in co-pending application Serial No. 333,660 referred to.

Paralleling the telescoping shafts a locking bar A55 is mounted in suitable guideways A56. This bar has the locking web A57 for engaging the teeth of the register driving gears A27 to lock said gears against rotation. The web, however, has the unlocking notches A58 equal in number to the transmission pinions A41, and disposed in the same plane with said pinions, so that when said pinions are in mesh with a set of the driving gears, the teeth of said driving gears will extend in said notches and the gears will be free to rotate, all the other

driving gears, however, being in locking engagement with the locking web and thus prevented from rotation. The bar A55 is moved with the transmission pinion shafts, being connected with the inner shaft A40^c by means of an arm A59 extending from the bar and engaging at its end in the slot A60 formed in the bearing sleeve A47. Longitudinal movement, therefore, of the screw shaft, and movement of the transmission pinion shafts therewith, will result in simultaneous longitudinal movement of the bar A55 with said shafts.

The shaft M122 of the master machine carries the drive gears E4^a, E4^b and E4^c for driving the multiplying mechanism sets E^a, E^b and E^c. Shafting and gearing E49 also connects the master machine with each of the shafts E49^a, E49^b and E49^c which control the selector mechanism of the multiplying mechanism. The multiplying mechanism construction is shown in full detail in my copending application, Serial No. 446,895 already referred to, and it is not thought necessary to here show all these details. As shown in said co-pending application, the gears E4 are driven in accordance with the set-up in the master machine, while the shafts E49 connect through suitable gearing with the selector shaft E25 of the multiplying mechanisms, as shown in the copending application, so that after a set-up of the electro-magnets E37, rotation of the shafts E49 will cause the proper multiplying gear sets to be connected in for service. In the co-pending application, the multiplying gear sets of the units order are shown as normally in mesh. Instead of this construction, I use in the present application an additional gear E11_o, which normally has its teeth in engagement with the teeth on the locking member E8_o. The operation, however, is the same as that in said co-pending application, namely, that upon energization of one electromagnet and rotation of the corresponding shaft E49, the gears of the corresponding multiplying set are brought into mesh and at the same time the universal bar E55 is moved to withdraw the gear E11_o from locking engagement with the block E8_o, so that upon rotation of the corresponding driving gear E4, the gears of the connected in multiplying set may rotate. Each multiplying mechanism set has also multiplying gear sets ranging from 0 to 9; that is, in each set the multiplying range is from 0 to 9. The shafts E12^{a--b--c}, of the multiplying mechanism sets, terminate in pinions 17^{a--b--c}, and these pinions mesh with the transmission gears E19^{a--b--c}. The transmission gear E19^a is pivoted on the tubular shaft E38^a, and has a key for engaging in the keyway E40^a, the gear being confined against sidewise movement in the slot 65 A61^a in the bearing A39^a. The transmission

gear E19^b is pivoted on the tubular shaft A38^b, and has a key engaging in the keyway A40^b, said gear being confined in slot A61^b in bearing A39^b. The transmission gear E19^c is pivoted on the inner shaft A38^c, and has a key engaging in slot A40^c. Each shaft can, therefore, slide through the transmission gear mounted thereon, and will be rotated upon rotation of the gear.

After the above description of the various parts and mechanisms, the operation will be clear. Take, for example, in a time-keeping account, the multiplication of time and rate elements to obtain wage elements. Suppose that the time element is 56 hours, and the rate element 27¢ per hour. If the apparatus shown were associated with the automatic system of my co-pending application, Serial No. 446,895, the number of the workmen to be credited with the wages would be set up on one of the keyboards, which would result automatically in the operation of the rate keyboard to set up the rate element on the multiplying mechanism, and operation of the time keyboard to set up the time element in the master machine, and the master machine then operating the multiplying mechanism, the rate and time elements would be combined and set up as the wage element on the register mechanism through the transmission gears and pinions. Instead of having the rate and time elements set up automatically upon set-up of the workman's number, the rate and time keyboards could be directly actuated manually. The rate element in the example is 27, and therefore the 7's digit electromagnet of the units multiplying mechanism set E^a will be energized, and in the tens order multiplying mechanism set E^b the 2's digit electromagnet will be energized. In the master machine, the number 56 will be set up in the manner which has already been carefully described in co-pending applications, the master machine operating first to carry the driving mechanism into the field of the units order, then causing operation of the driving mechanism to rotate the shaft M66 in proportion to the number set up in the units order; the driving mechanism being then carried into the field of the tens order and again operated to be rotated in proportion to the units set-up, and so on, throughout the range of master machine orders. The shaft M66 of the master machine controls the movement of the driving mechanism into the various order fields, and the shaft M122 controls the transmission of the order set-up to external mechanism. In the arrangement shown in the present application, the shaft M66 connects with the screw shift shaft A48 and with the set-up mechanism of the multiplying mechanisms, as has already been explained, and the shaft M122 connects with the multiplying

ing mechanism driving gears $E4^{a-b-c}$. In the ordinary position, as shown, the transmission gears $A41^a$ and $A41^b$ are in mesh with the units and tens driving gears of the register mechanism, and these gears extend 5 into the unlocking slots in the locking bar $A57$.

We have the electromagnets 2 and 7 energized, and the corresponding clutch mechanism brought into service in the tens and units orders, respectively, of the multiplying mechanism, and in the master machine we have the set-up 56. When the master machine now starts, the shaft M66 is first 10 rotated to move the screw shaft and the rod A55 to the left one order, to carry the transmission pinions $A41^{a-b-c}$, into mesh respectively with the units, tens and hundreds register mechanism driving wheels A27, the 15 unlocking notches in the locking bar A57 being then arranged so that these drive wheels are free to rotate. Simultaneously with this movement of the transmission pinions, the gearing E49 is driven, and the 20 cam wheels E45 of the multiplying mechanism rotated to operate the clutch mechanism to connect in the 7's digit multiplying set gears in the units order multiplying mechanism and to connect in the 2's digit multiplying set gears in 25 the tens multiplying mechanism. After this set-up in the multiplying mechanism sets has been completed the shaft M66 30 nism of the master machine is brought into the field of the units order, in which the number 6 is set up, and therefore, when the shaft M122 is rotated, it is given .6 revolutions, and the driving gears $E4^{a-b-c}$ are simultaneously given .6 revolutions. The 35 gearing relations between the gears $E4^{a-b-c}$ and the pinions $E5^{a-b-c}$ is 1 to 10, and therefore pinions $E5^{a-b-c}$ and the shafts $E6^{a-b-c}$, on which they are mounted, will be rotated 6 revolutions. In the units 40 order multiplying mechanism set, the 7's digit multiplying gears are in mesh, and therefore the six revolutions of the units shaft $E6^a$ will be transformed into 42 revolutions of the units shaft $E12^a$.

50 The gearing relation between the pinions $E17^{a-b-c}$ and the transmission gears $E19^{a-b-c}$, respectively, is 10 to 1. The 42 revolutions of the units shaft $E12^a$ will result in 4.2 revolutions of the gear $E19^a$, shaft 55 $A38^a$ and the transmission pinion $A41^a$. The gearing relation between the transmission pinions $A41^{a-b-c}$ and the register drive gears A27, is 2 to 1, on account of the differential mechanism. When the units transmission 60 pinion, therefore, makes 4.2 revolutions, the amount 42 is carried thereby into the register. However, at the same time that this entry is made, an entry is made simultaneously by means of the transmission pinion $A41^b$ connected with the tens multiplying 65

mechanism set. The shaft M122 rotating .6 of a revolution, causes 6 revolutions of shaft $E6^b$ of the tens multiplying mechanism set and the 2's digit multiplying train being set for operation, the 6 revolutions are transformed into 12 revolutions of the shaft $E12^b$, which results in 1.2 revolutions of the shaft $A38^b$ and of the pinion $A41^b$. This 1.2 revolutions results in the entry of 12 in the tens order. Upon the 4.2 revolutions of the 75 units driving gear, the units order indicating mechanism will indicate 2, and 4 will be carried into the tens order through the carry-over mechanism. However, as the tens order driving gear is driven 1.2 revolutions by the transmission pinion $A41^b$, 2 will be added to the 4 and 6 will be the indication in the tens order, while the hundreds order will indicate 1, having been moved to this position by the carry-over mechanism when 80 1.2 revolution was made in the tens order, and the total indication will be 162, which is the result of the multiplication of 27 by 6. After this concurrent entry in the register, the shaft M122 stops and the screw shaft 90 A48 is advanced another order to carry the transmission pinions $A41^{a-b-c}$ into mesh respectively with the tens, hundreds and thousands register driving gears, the locking shaft A55 being likewise shifted to unlock said driving wheels and to re-lock the units drive wheel. The master machine driving mechanism is also brought into the field of the tens order, in which 5 has been set up. The multiplying mechanism, however, retains its set up of 27. Shaft M122 is now given .5 revolutions, and the drive wheels $E4^{a-b-c}$ are simultaneously given .5 revolutions. On account of the gearing 95 relations and the set-up of the 7's digit in 100 the units multiplying mechanism set E^a , the shaft $A38^a$ will be given 3.5 revolutions, and the transmission pinions having been advanced an order, this 3.5 revolutions will be transmitted from the pinion $A41^a$ to the tens 105 order register driving wheel, and there will be 3.5 revolutions of this gear. The 2's digit being set up in the tens multiplying mechanism set E^b , the shaft $A38^b$ will be given 1 110 revolutions, and the pinion $A41^b$ being in 115 mesh with the hundreds orders register driving wheel, this wheel will be given 1 revolution. We therefore have had a simultaneous actuation in the register of 3.5 revolutions through the tens wheel and 1 revolution through the hundreds driving wheel. As a result of the previous entry when 6 was the multiplicand, the tens wheel indicated 6, and the 3.5 revolutions through the tens 120 wheel will cause the addition of 5 units to the tens wheel and cause a carry-over operation into the hundreds order and leave the indication on the tens order, 1. In the hundreds order, after the first entry the indication is 1. The entry of the 3.5 revolutions 125

130

through the tens order added 3 units to the hundreds order, and this together with the 1 already in said order and the 1 unit received from the tens order through the 5 carry-over mechanism, will leave an indication on the hundreds order of 5. The entry of 1 revolution through the hundreds order from the transmission pinion A38^b did not add anything to the hundreds order, but the 10 carry-over mechanism was actuated one unit and the indication in the thousands order made 1. We therefore now have the final indication of 1512 on the register, which is the result of the multiplication of 15 27 by 56.

There being no set-ups in the master machine beyond the tens order, the rotation of the shaft M66 will be reversed, as has been described in co-pending application Serial 20 No. 333,660, and screw shaft A48 will be drawn to the right to its ordinary position, with the transmission pinions A41^b and A41^c in mesh respectively with the units and tens register driving gears. The transmission mechanism E49 will also receive reversed rotation, and the clutch mechanisms in the multiplying mechanisms will be released and the multiplying set gears restored to their normal position, as shown in the 30 drawing.

It will thus be seen that after the parts driven by the master machine shaft M66 have been properly set with reference to one order, and the machine shaft M122 35 started, all the steps of the multiplying cycle will be concurrent and simultaneous. The multiplying operation, the positive entry of the result and the operation of the register carry-over mechanism will all be 40 simultaneously and concurrently performed, and upon the completion of rotation of shaft M122, all the steps will have been completed and the result of the cycle indicated. No matter how many digits have been set up in 45 the multiplying mechanism, all the orders of the set-up number will be multiplied simultaneously by any order set up in the master machine and concurrently with each of such multiplications the result of the 50 multiplication will be carried into the register and indicated. It is very evident that a considerable saving of time is effected by this automatic arrangement. The time consumed in carrying through a multiplying 55 operation will be the same, no matter how many digits the rate element involves.

As shown, each indicating order set of the register includes a commutator A62 having 10 segments adapted to be engaged by 60 brushes A63 to control circuits of indicating or other apparatus. In the system shown in my co-pending application, Serial No. 446,895, these circuits include the wage keyboard setting up electromagnets.

65 As already stated, the apparatus I have

shown for carrying out my invention is quite diagrammatic, and I do not, therefore, limit myself to the construction and arrangement shown.

While the description largely explains the 70 invention as applicable to my co-pending application, Serial No. 446,895, and designates the factors for multiplication as time and wage elements, it is obvious that the factors may be abstract quantities of any 75 character.

Many forms of apparatus could be used for carrying out the features of my invention, and the arrangement shown is only one of the many forms. 80

Having described the features of my invention, I desire to secure the following claims by Letters Patent:

1. In multiplying mechanism, the combination of multiplying sets each representing 85 a decimal order, means for simultaneously setting up a number of such sets, re-order digits of a number to be multiplied, and means for simultaneously driving the multiplying sets in accordance with an order digit 90 of a number by which the set up number is to be multiplied.

2. In multiplying mechanism, the combination of multiplying sets each representing a decimal order, means for simultaneously 95 setting up a number of such sets, re-order digits of a number to be multiplied, means for simultaneously driving the multiplying sets in accordance with an order digit of a number by which the set up number is to 100 be multiplied, and register mechanism for simultaneously receiving the various order products and for simultaneously arranging them to indicate the final product.

3. In multiplying mechanism of the class 105 described, the combination of a plurality of multiplying sets each representing an order of a number to be multiplied, means for setting up in said multiplying sets the order digits of the number to be multiplied, driving mechanism connected with the multiplying sets to cause simultaneous operation thereof in accordance with a number by which the set up number is to be multiplied, register mechanism, and transmission mechanism between the register mechanism and the multiplying sets for transmitting the various order products to the register mechanism. 115

4. In multiplying mechanism of the class 120 described, the combination of a plurality of multiplying sets each representing a decimal order of numbers to be multiplied, means whereby the order digits of a number to be multiplied may be set up in the respective multiplying sets in any sequence or combination, driving means for simultaneously driving the multiplying sets in accordance with a number by which the set up number is to be multiplied whereby the 125 130

various order products are obtained simultaneously, and register mechanism for receiving and accumulating the order products to indicate the final product of the 5 numbers multiplied together.

5. In multiplying mechanism of the class described, the combination of a plurality of multiplying sets each representing a decimal order of numbers to be multiplied, 10 means whereby the order digits of a number to be multiplied may be set up in the respective multiplying sets in any sequence or combination, driving means for simultaneously driving the multiplying sets in accordance with a number by which the set up 15 number is to be multiplied whereby the various order products are obtained simultaneously, and differential register mechanism for simultaneously receiving the various order products and accumulating them to indicate the final product.

6. In multiplying mechanism of the class described, the combination of a plurality of multiplying sets each representing a decimal order, means whereby the order digits of a number to be multiplied may be set up in the respective order multiplying sets in any sequence or combination, driving means for causing simultaneous operation of the 25 multiplying sets in accordance with a number by which the set up number is to be multiplied whereby the various order multiplications are simultaneously performed, register mechanism connected with the 30 multiplying sets, and means for causing said register mechanism to receive the various order products and to accumulate them simultaneously with the operation of the driving mechanism and multiplying sets to 35 indicate the final product at the end of the operation of all the mechanisms.

7. In a system of the class described, the combination of a plurality of multiplying sets each representing a different decimal order, a plurality of multiplying gear trains in each set ranging from between the ratio of one to one to the ratio of nine to nine, 45 means for setting up for operation in each order set the gear train corresponding to the digit in the same order of a number to be multiplied, driving means connected with one end of the gear trains for simultaneously driving the selected gear trains in accordance with a number by which the set up 50 number is to be multiplied whereby the various order multiplications are performed simultaneously, and register mechanism connected with the other end of the gear trains for receiving and accumulating the 55 various order products to indicate the final product of the two numbers multiplied.

8. In a system of the class described, the combination of a plurality of multiplying sets each representing a different decimal order, a plurality of multiplying gear trains 60

in each set ranging from between the ratio of one to one to the ratio of nine to nine, means for setting up for operation in each order set the gear train corresponding to the digit in the same order of a number to be multiplied, driving means connected with one end of the gear trains for simultaneously driving the selected gear trains in accordance with a number by which the set up number is to be multiplied whereby the various order multiplications are performed simultaneously, and differential register mechanism connected with the other ends of the gear trains to simultaneously receive the various order products and to accumulate these products to indicate the complete and final product.

9. In a system of the class described, the combination of a plurality of multiplying sets each representing a different decimal order, a plurality of multiplying gear trains in each set ranging from between the ratio of one to one to the ratio of nine to nine, 85 means for selecting for operation in each order set the multiplying train corresponding with the digit in the same order of a number to be multiplied, driving means connected with one end of the gear trains, order transmission members connected with the other ends of the multiplying trains, 90 register mechanism having order members connected with the order driving members, and means for causing operation of the driving mechanism in accordance with a number by which the set up number is to be multiplied whereby the various order products are simultaneously transferred to the register mechanism and there accumulated into the final product.

10. In a multiplying mechanism of the class described, the combination of a plurality of multiplying sets each representing a different decimal order, nine multiplying trains in each set ranging from the ratio of one to one to the ratio of nine to nine, means for selecting for operation the multiplying trains in the various sets representative of a number to be multiplied, driving mechanism connected with one end of the multiplying trains and adapted to be driven successively in accordance with the order digits of a number by which the set up number is to be multiplied, a transmission member connected with the other end of the multiplying trains of each set, register mechanism having order members adapted for connection with said transmission members, each operation of the driving mechanism causing simultaneous operation of the selected multiplying trains to thereby cause simultaneous multiplication of the various set up order digits by the multiplying order digit, said transmission members simultaneously transferring the various order products into the register mechanism to cause 115

- said register mechanism to accumulate said products and to indicate the final product of each multiplication by a digit of the multiplying number, and means operative 5 after each actuation of the driving mechanism for shifting the transmission members from the last actuated set of order members to the next higher set of order members of the register mechanism, whereby said register mechanism during the next operation of the driving mechanism may receive the various products resulting upon multiplication of the set up digits by the next order digit of the multiplying number.
- 10 11. In multiplying mechanism of the class described, the combination of multiplying mechanism, means for setting up in said multiplying mechanism an entire number to be multiplied, driving mechanism for said multiplying mechanism for causing successive operation of said multiplying mechanism in accordance with the order digits of a number by which the set up number is to be multiplied, register mechanism connected 15 with the multiplying mechanism, and means for causing said multiplying mechanism and register mechanism to operate simultaneously with each operation of the driving mechanism whereby the various order products of the set-up number by a digit of the multiplying number are simultaneously obtained and such products simultaneously received and accumulated in the register.
- 20 12. In a wage accounting system, the combination of multiplying sets each representing a different decimal order, multiplying trains in each set, means for setting up in each set a multiplying train corresponding to the corresponding order digit of a rate element, driving mechanism connected with the multiplying trains and controlled to operate successively in accordance with the order digits of a time element, register mechanism connected with the trains to receive 25 the products of the multiplications of the rate element by the various orders of the time element and to accumulate said multiplications to indicate the wage element.
- 30 13. In a multiplying machine, the combination of a plurality of multiplying sets, each representing a decimal order, means whereby the order digits of a multiplicand may be set up in the various multiplying sets, register mechanism having order driving 35 members, order transmission members for connecting the register order members with the multiplying units, a master-machine, means for setting up in decimal orders the order digits of a multiplier, driving mechanism in the master machine, shift mechanism connected with the order transmission members and driven in the master machine to successively associate the master machine driving mechanism with the order 40 digits of the multiplier, and to simulta- neously shift the transmission members from one set of orders of the register mechanism to the next set, said shift mechanism and driving mechanism being actuated alternately, said master machine driving mechanism being connected with the multiplying sets to simultaneously multiply the multiplying sets after each shift operation and in accordance with the order digit of multiplier associated with the driving mechanism, 45 whereby the order digits of the multiplicand are simultaneously multiplied consecutively by the multiplier digits after each shift operation and the resultant decimal product entered in the register mechanism and all the decimal products accumulated in the register mechanism.
- 50 14. In a multiplying machine, the combination of a plurality of multiplying sets each representing a different decimal order, means for setting up in said sets the order digits of a multiplicand, a master machine, driving mechanism for said master machine connected with all the multiplying sets to cause simultaneous operation thereof, means 55 for setting up in said master machine in decimal rows the order digits of a multiplier, shift mechanism driven by the master machine to associate the driving mechanism successively with the order rows in which the multiplier digits are set up, register mechanism having order driving members, order transmission members connected with the shift mechanism to be shifted therewith, from one set of register order members to 60 another set of such register order mechanisms transmission mechanism connecting the transmission members with the multiplying units, said master machine mechanism and driving mechanism operating alternately whereby after each shift operation, the order digits of the set up multiplicand are simultaneously multiplied by the corresponding order digit of the master machine in which the driving mechanism is associated and whereby the resultant decimal products are transmitted through the transmission mechanism to the transmission members and to connect register order members and whereby the final product is accumulated in the register mechanism.
- 65 15. In a wage accounting system, the combination of a plurality of multiplying sets, each being a different decimal order, members for setting up in said multiplying sets in any order or combination the various order digits of a rate element, a master machine, driving mechanism controlled by the master machine and connected with the multiplying sets to cause simultaneous operation thereof, means for setting up in decimal orders the digits of a time element, shift mechanism driven by the master machine for associating the master machine driving mechanism consecutively with the 70

decimal orders, means for causing the driving mechanism to operate in accordance with the digit set up in the order with which said driving mechanism has been associated, register mechanism comprising order driving members, transmission members connected with the multiplying sets and connected with the shift mechanism to be shifted from one group of register order members to another group, said shift mechanism and drive mechanism being actuated alternately whereby the digits of the rate elements are simultaneously multiplied by the consecutive order digits of the time elements and the decimal products transmitted to the register mechanism to be there accumulated into resultant wage element.

16. The combination of a plurality of multiplying sets, each set having a plurality of multiplying ratios, common means for actuating the same, and a register directly actuated by said multiplying sets for totalizing said actuations and means for automatically connecting each multiplying set to the actuating means at a desired ratio.

17. The combination of a plurality of multiplying sets, each set having a plurality of multiplying ratios, common means for actuating the same a predetermined amount, and a register directly actuated by said multiplying sets for totalizing said actuation and means for automatically connecting each multiplying set to the actuating means at a desired ratio.

18. The combination of a plurality of multiplying sets, each set having a plurality of multiplying ratios, common means for actuating the same, and a register directly actuated by said multiplying sets for simultaneously totalizing said actuation and

means for automatically connecting each multiplying set to the actuating means at a desired ratio.

19. The combination of a register, a plurality of multiplying sets, a common actuating means, and devices for positively operating the register by simultaneous operation of the multiplying sets and means for automatically connecting each multiplying set to the actuating means at a variable ratio.

20. The combination of a register, a plurality of sets of gearing, a common actuating means, and devices for positively operating the register by simultaneous operation of the sets of gearing and means for automatically connecting each set of gearing to the actuating means at a variable ratio.

21. The combination of a plurality of multiplying sets, a driven device, and means for actuating the driven device through such sets at a rate equal to the added ratios of the multiplying sets and means for automatically connecting each multiplying set for actuation at a variable ratio.

22. The combination of a plurality of sets of gearing of different ratio, a driven device, and means for actuating the driven device through the sets of gearing at a rate equal to the added ratios of such sets of gearing and means for automatically connecting each set of gearing for actuation at a variable ratio.

In witness whereof, I hereunto subscribe my name this 7th day of April, A. D. 1910.

WILLIAM J. CRUMPTON.

Witnesses:

ALBERT G. McCALEB,
A. A. THOMAS.
